UNITED STATES PATENT OFFICE.

ALBERT HARRISON DE VOE, OF WESTFIELD, NEW JERSEY.

TOY.

Application filed November 26, 1920. Serial No. 426,559.

To all whom it may concern:

Be it known that I, ALBERT H. DE VOE, a citizen of the United States, residing at Westfield, in the county of Union and State 5 of New Jersey, have invented certain new and useful Improvements in Toys, of which the following is a specification.

This invention relates to improvements in amusement devices more particularly in 10 the nature of toys or games.

An object of this invention is to provide an improved amusement device resembling a watch and of a form readily permitting it to be carried in a garment pocket or in a 15 reticule.

Another object of this invention is to provide a toy or game of this character, which upon manual manipulation presents to view, in an indeterminate manner, one or more of 20 a plurality of symbols, characters, expressions and the like which may individually, successively or unitedly produce an amusing and entertaining result, or which may be employed for educational purposes.

25 A further object of this invention is to provide an indicating toy or game of the kind referred to with adjusting means whereby the view of certain of the symbols, &c. may be temporarily obstructed when 30 it is not desired to employ the same.

The invention has also for its object to provide an indicating toy or game of this character capable of being sustained and manipulated by either or both hands of an 35 operator, or which may be manipulated while in a garment pocket and brought to view without disturbing the position of the symbol or symbols attained by such manipulation.

40 The invention also comprehends means for maintaining the position of the symbol or symbols and the like in the interval between successive manipulations of the toy.

Other objects of the invention will be 45 apparent from the following description and claims.

To the attainment of the several objects of the present invention, the preferred embodiment thereof comprises a casing resembling a watch and of which the opposed faces are provided with apertures. Journaled within the casing are disks positioned closely adjacent the inner surfaces 50 of said opposed faces and upon which disks 55 are symbols, characters, expressions, messages and the like arranged at proper radial

distances to bring them into alignment with the face-apertures designed for viewing the symbol or expression appearing thereunder, the remainder being hidden by the casing. 60 In order to relatively move the apertures and the symbols appearing thereunder, in an indeterminate manner, to position different symbols under the respective apertures, the disks are carried by a spindle 65 journaled in the casing and mechanism is provided for spinning the disks an indeterminate distance in one direction and then in a reverse direction, the reverse movement being abruptly terminated by a suitable stop-device. Projecting through the casing is a finger, upon depression of which the disks are set in motion for the purpose described and which finger may be readily manipulated to this end by and 70 while sustaining the toy in an operator's hand.

The apertures referred to as provided in one of the faces of the toy are preferably arranged in groups. Should it be desired 80 to at times employ only one group, the other groups of apertures may be closed by a specially designed shutter arranged on the inner side of said face and which shutter may be adjusted by a stud projecting 85 through an arcuate slot in the casing face. The shutter in the present instance is frictionally maintained in its adjusted position.

In a modification herein illustrated two 90 disks are positioned so that symbols of each thereof are indicated and the disks are so arranged that they may move in unison or one independently of the other. In the latter instance, the one disk is preferably 95 maintained in a stationary position, so that the indicated symbols may remain in view while repositioning the symbols of the other disk.

In the accompanying drawings, Fig. 1 is 100 a plan view which may be arbitrarily termed as a top-plan, the plane surface shown in this figure being hereinafter termed the top or upper surface for the sake of clearness. Fig. 2 is a top plan view 105 of the shutter shown detached. Fig. 3 is a top plan view with the upper casing and shutter removed. Fig. 4 is a view similar to Fig. 3 but also omitting the upper symbol-carrying disk to better show the actuating mechanism. Fig. 5 is a bottom plan view with the lower casing partly broken 110

away to show a portion of the lower disk. Fig. 6 is a sectional view substantially on the line $x-x$, Fig. 7. Fig. 7 is a sectional view substantially on the line $y-y$, of Fig. 5 1, shown enlarged. Fig. 8 is a detail perspective view of the actuating mechanism. Fig. 9 is a sectional view illustrating a modified form of disk arrangement.

Referring to the drawings, the toy or 10 game in the preferred embodiment, comprises a casing constructed in two sections, of which the upper section 1 is substantially flat and terminates in a peripheral, substantially circular flange 2. The lower 15 section 3 is of a form similar to the section 1, but having its peripheral flange formed with a laterally offset rib 4 throughout its circumference. The rib 4 frictionally embraces the flange 2 as particularly illustrated in Fig. 7 to unite the two sections into a form closely resembling a watch. The section 1 is provided with indicating means comprising a group of apertures as 5, a second group of apertures, as 6, an 20 elongated aperture 7 and an arcuate slot 8, while the section 3 has an elongated aperture 9, all for a purpose to be hereinafter described. Each of the apertures of group 5 are radially equidistant and are radially 25 non-equidistant with respect to the radially equidistant apertures of group 6. It is to be understood, however, that broadly the invention is not limited to the precise form and arrangement of the apertures referred 30 to as they may obviously be formed and arranged in any desired manner.

Positioned closely adjacent the inner flat surface of section 1 of the casing and journaled upon a hub 10 formed substantially centrally thereof is a shutter 11 provided with a plurality of peripheral lugs, as 12. These lugs 12 project through slits, as 13, formed in the flange 2 and frictionally engage the walls of these slits to retain 45 the shutter in adjusted positions. The shutter is formed with groups of apertures 14 and 15 and with an elongated aperture 16 corresponding in spacing and radial distances to enable them to be alined respectively with apertures 5, 6 and 7 in the casing. Projecting from the shutter 11 and through the arcuate slot 8 is a stud 17 by 50 means of which the shutter may be adjusted. In the position of the stud 17 as shown in Fig. 1, the apertures 5 of the casing and 14 of the shutter coincide, while the remaining apertures in section 1 are closed by the body of the shutter. By moving stud 17 counter-clockwise to a point 55 half way between the position of Fig. 1 and the end of the slot, the apertures 5 are closed and the apertures 6 are opened by alinement therewith of the apertures 15 of the shutter. In both of these positions 60 the elongated aperture 7 is closed, but by

now moving the stud still further and to the extreme end of the slot, both apertures 5 and 6 are closed while the aperture 7 is opened. It will thus be seen that all of the apertures of one group may be closed and those of another group opened simultaneously.

A spindle 18 is formed with reduced ends 18^a journaled in sections 1 and 3 of the casing, which sections are preferably slightly enlarged centrally of their outer faces to afford a firmer bearing for the spindle. A portion 18^b of the spindle adjacent the upper of the reduced ends 18^a thereof is slightly larger than the end 18^a, but is of less diameter than the main portion of the spindle and thereby affords a shoulder against which is rigidly forced a peripherally serrated disk 19 forming one member of coacting stop devices to be later referred to. Secured in 80 superposed relation upon disk 19 by screws, as 20, is a spacing washer 21 and a symbol-carrying disk 22. The upper face of this disk 22 may carry a plurality of numbers, letters, characters, expressions, messages and the like, which are herein termed symbols for the sake of simplicity and are arranged so that certain groups of them may be viewed through the several apertures, when opened as described. It will be obvious that rotation of the spindle 18 will position different combinations of these symbols in alinement with the apertures and that symbols may be provided producing a very amusing and entertaining combination. For instance, the 90 mere arrangement of letters of the alphabet may produce amusing combinations of words; numbers may be employed to teach arithmetical problems, oracular signs corresponding with interpretation books either 100 specially provided or of long standing may be employed, likewise messages, dominoes &c. Upon the opposite end of the spindle is secured another disk 23 positioned adjacent the inner surface of the lower section 3 of 110 the casing. Symbols carried by this disk may be viewed through the aperture 9 which is constantly open.

It is of course preferable in a toy of this character to provide means whereby the 115 stopping position of the disks is manually indeterminate. To this end a special driving device for the spindle is employed which will now be described in detail. A segmental plate 24 is positioned within the casing by 120 means of a pin 25 on the latter entering a notch 26 in the plate. The circular edge of the plate 24 rests upon a shoulder 27 formed on section 3 of the casing and is held thereupon by the flange 2 of section 1. Pivotally 125 supported upon opposite sides of the plate 24, by means of a stud-screw 28 passing through an aperture 29, are two operating or driving arms 30 and 31 having pivotal apertures 32 and 33. The arm 30 is formed 130

with an operating finger 34, projecting through a slot 35 formed in section 3 of the casing and in convenient position for manipulation. The free end of arm 30 is provided with an apertured, offset ear 36 to which is secured one end of a flexible driving element 37 embracing the spindle 18 and of which the other end is secured to a similar ear 38 provided on the arm 31. In order to tension the driving element and cause it to frictionally grip the spindle 18, the free end of the arm 30 is yieldingly urged away from the spindle by means of a spring 39, of which one end is secured upon the plate 24 and the other end bears against a lug 40 formed on the arm 30, the spring intermediate its ends being sustained by a pin 41 on the plate 24. Likewise the free end of the arm 31 is yieldingly urged away from the spindle but in the opposite direction under the action of a spring 42 of which one end is secured upon the arm 30 and of which the other end bears against a lug 43 provided on the arm 31, the spring intermediate its ends being afforded a fulcrum point by the screw 44 threaded into the arm 30.

From the foregoing description it will be apparent that the normal tendency is to maintain the flexible element 37 in driving engagement with the spindle 18 and that under the action of the spring 39, the operating finger 34 is normally projected beyond the casing, ready for manipulation, as illustrated in the several figures in the accompanying drawings. During manipulation, when the finger 34 is depressed, the arms 30 and 31 maintain their angular relationship under the spring action described and consequently the spindle 18 is caused to revolve due to the frictional grip thereupon of the flexible element 37. However, the ear 38 is in alinement with the plate 24 and upon contact therewith, the angular relationship of the arms 30 and 31 is destroyed, thereby slackening the driving element 37 and permitting free rotation of the spindle under the induced momentum. When the finger 34 is now released, the arms 30 and 31 immediately resume their angular relationship and thereby cause a reverse rotation of the spindle 18 by the action of the spring 39 to return the parts to their original position determined by the engagement of arm 30 with the casing. In attaining this position, a pin 45 provided on the arm 31 enters a serration on the stop disk 19 heretofore referred to, which not only serves to maintain the spindle 18 stationary between successive manipulations of the operating finger, but also insures correct alinement of the symbols with the open casing apertures.

While the momentum induced in the spindle is to some extent dependent upon the speed of depression of the operating

finger, it will be readily apparent that the stopping position can in no wise be predetermined manually and therefore the symbol or group of symbols appearing to view produce the unexpected and amusing results 70 so essential in a toy of this character.

In the modification illustrated in Fig. 9 of the drawings, the casing comprising the sections 1 and 3 may be of the same general form as in the preferred embodiment 75 described. In the modification, however, the spindle 46, which may be driven in substantially the same manner as the spindle 18, is not directly journaled in the casing, but is axially apertured for the reception of the shank of a disk-shifting pin 47 which also passes through the usual journal aperture in the casing and thereby forms an axle of the spindle. Suitably secured upon the pin 47 is a secondary symbol-carrying disk 48, 80 from the opposite faces of which projects a stud 49. In the position illustrated in Fig. 9, the stud 49 is entered in a suitable aperture in the usual symbol-carrying disk 22, whereby it is caused to partake of the rotary 85 movements of the latter. After manipulation of the spindle actuating means, the symbols of both disks 22 and 48 may be indicated by or viewed through apertures, as 50 and 51, owing to the shorter diameter of disk 48. 90 Now should it be desired to throw disk 48 out of operation, it is disconnected from its driving means by merely pulling on the pin 47, thus disengaging the stud 49 from the disk 22. The stud 49 may now be seated in 100 an aperture 52 provided in the casing, whereby the disk 48 is held stationary during manipulation of the disk 22. In other words, a symbol or group of symbols indicated by disk 48 following rotation thereof 105 with disk 22 may be maintained in indicated position while other symbols are indicated on disk 22 for combination reading.

The operation of the toy will be readily apparent from the foregoing description and a resume thereof is deemed unnecessary. It is to be understood that important features of this toy are its portability in a garment pocket or reticule; its watch-like design rendering it appealing to children; its simplicity of construction; its ease of manipulation by compression of an operator's hand or by the operator's fingers, and its unexpected results, and that various modifications in the precise form and arrangement 110 115 120 may readily be made and remain within the spirit and scope of this invention.

Having thus set forth the nature of the invention, what I claim herein is—

1. A toy including a plurality of symbols, 125 a plurality of indicating devices, means for relatively moving the symbols and said indicating devices for the purpose of relatively repositioning the symbols and the indicating devices, and adjusting means for 130

- at will rendering a portion of said indicating devices temporarily ineffective.
2. A toy comprising a casing provided with a symbol-viewing aperture, a symbol-carrying disk sustained by said casing, means for relatively rotating said casing and said disk to aline a symbol with said aperture, and a shutter slidably sustained by said casing for closing said aperture.
- 10 3. A toy comprising a casing provided with a group of radially equidistant apertures, a disk carrying a plurality of symbols radially alined with said apertures, means for spinning said disk, and means disengaged from said disk during the spinning thereof acting to automatically arrest the rotation of said disk to aline symbols with said apertures.
4. A toy comprising a casing provided with radially non-equidistant groups of radially equidistant apertures, symbols positioned for view through said apertures, and means for simultaneously closing all the apertures of a group.
- 25 5. A toy comprising a casing provided with groups of apertures, symbols positioned for view through said apertures, and means for closing the apertures of one group and simultaneously opening the apertures of another group.
- 30 6. A toy having a watch-like casing provided with an aperture in each of the opposite faces thereof, symbols positioned for view through said apertures, and means for repositioning said symbols with respect to said apertures in an indeterminate manner.
- 35 7. A toy comprising a watch-like casing, a plurality of disks journaled within said casing, a plurality of symbols carried by each of said disks, means permitting a view through opposite sides of the casing of only a portion of said symbols carried by the disk adjacent thereto, and means for rotating said disks.
- 40 8. An indicating toy having a casing, a rotary spindle journaled in said casing, and means for rotating the spindle including a flexible driving element embracing said spindle, pivotally supported operating arms connected with opposite ends of said driving element, means for yieldingly maintaining the free ends of said arms in position to tension said driving element to thereby cause
- the latter to frictionally grip said spindle, and a stop for one of said arms to release 55 said driving element and permit free rotation of said spindle.
9. An indicating toy having a casing, a rotary spindle journaled in said casing, and means for rotating the spindle, including 60 a flexible driving element embracing the spindle, means for causing frictional engagement of said driving element with said spindle, means acting to suddenly release said driving element to permit free rotation of the spindle, and an operating finger projecting beyond the casing.
10. An indicating toy having a casing, a rotary spindle journaled in said casing, and means for rotating the spindle including a 70 flexible driving element frictionally gripping the spindle to rotate the same in reverse directions, and coacting stop devices for normally maintaining the spindle stationary.
- 75 11. An indicating toy having a casing, a rotary spindle journaled in said casing, and means for rotating the spindle including a flexible driving element frictionally gripping the spindle to rotate the same in reverse directions, an operating finger projecting beyond the casing, means permitting sudden release of said driving element to allow free rotation of the spindle, and coacting stop devices for normally maintaining the spindle stationary.
- 80 12. A toy including a plurality of symbol-carrying disks, indicating devices for the symbols of each of said disks, means for rotating said disks in unison, means for throwing one of said disks out of operative relation with its rotating means, and a device for maintaining the inoperative disk stationary while actuating said driving means.
- 90 13. A toy including a symbol-carrying element, an indicating device for the symbols of said element, actuating means for relatively moving the element and the indicating device for indicating different symbols, and means for rendering said actuating means ineffective.
- 95 In testimony whereof I affix my signature.

ALBERT HARRISON DE VOE.
